CONDENSER DEVICE FOR REFRIGERATORS

Roland H. Money, Cincinnati, Ohio, assignor to
The Crosley Radio Corporation, Cincinnati,
Ohio, a corporation of Ohio

Application May 28, 1936, Serial No. 82,299

6 Claims. (Cl. 257—36)

My invention relates to condensers for domestic refrigerators in particular, and has as its object the provision of an air cooled condenser unit, which is of extensive size, suitable for use with a domestic refrigerator without use of fans or water for cooling, and yet can be packed within a compass which does not require any substantial increase in packing expense.

The plan of placing the condenser for a domestic system in a position hanging at the back of the cabinet, has called for such a large condenser that it has proven quite a problem to provide a shipping package which permits of shipping it safely, without adding substantially to the size and weight of the shipping package. It is of apparent advantage to make a folding type of condenser which can be compactly arranged for shipment, and yet which can be readily and easily unfolded and arranged in place for use.

More specifically it is my object to provide a condenser which can be bent at the central part, for example, so that it can be folded under the compressor unit in shipping. In the drawing 25 I have illustrated my preferred form of structure which is simple, and which permits of easy unfolding and of easy securing the condenser assembly in bent shape or straightened out as in use.

I refer to the appended claims for a statement of the invention inherent in the structure illustrated and described.

In the drawing:

Fig. 1 is a side elevation of a refrigerator with parts broken away and certain parts in section.

Fig. 2 is an enlarged elevation of my improved condenser as seen from the right side of Fig. 1.

Fig. 3 is an enlarged fragmentary side elevation of the condenser showing how I may provide 40 a bendable joint therein.

Fig. 4 is a section taken along line 4—4 of Fig. 3.

Fig. 5 is a fragmentary side elevation of the condenser when in its bent position.

Fig. 6 is a fragmentary side elevation of the 45 upper left hand side member.

Fig. 7 is a fragmentary side elevation of the lower left hand side member, and

Fig. 8 is a plan view of the tubing support used at the bendable portion of my condenser.

I have shown a refrigerator cabinet 1, and at the rear thereof a condenser unit marked 2. There are pipes 3 and 4 connecting up the condenser with the rest of the refrigeration unit. The pipe 3 extends to the compressor 5 from the 55 top of the condenser, and the pipe 4 extends up

from the bottom of the condenser to the top where it passes inwardly near the pipe 3 and is connected to the evaporator 6 of the unit.

The mode of shipping a refrigerator is to ship the cabinet in one package and ship the refrigeration unit, fully charged and ready to operate in another package. The cabinet, as per present practice has an upper compartment in it, which is open to the back of the refrigerator, and the refrigeration unit is set into place by inserting it 10 into this compartment from the back, so that the evaporator projects down through an insulated orifice, into the refrigeration compartment of the cabinet.

The problem for which my invention is a solution, is how to arrange the condenser of the new long type, with the refrigeration unit, so that it can be shipped in a compact form, already connected up with the other parts of the unit.

The preferred mode of accomplishing this is 20 illustrated in the drawing. The particular condenser is made up of copper tubing 6, which is arranged in a series of parallel loops with radiating fins 7, passing down through the assembly. As most simply made, the fins have holes in them, 25 the copper tubes are bent into a hair pin arrangement and then thrust through the fins, whereupon connectors 8 are welded into place to join the hair pin like arrangements and form a continuous sinuous tube, for the condensation action. As shown the fins for the upper half of 30 the condenser are separate from those of the lower half.

The outside strips are thicker than the fins and preferably made of angle iron. They too 35 have holes in them for passage of the tubing, and are assembled with the tubing when the fins are added. I provide in the present embodiment two upper outside strips 9 and two lower outside strips 10. Also, preferably, I provide for a different tubing arrangement at the point where the upper and lower outside strips are joined, for a purpose which will be noted. Here I interrupt the hair pin like arrangement and instead provide for two straight tubing sections 11, 11, heavier 40 union fittings 12 at their ends, and an S-shaped piece of copper tubing 13, which is welded into each union.

The support for the ends of the straight portion of tubing section 13, are two metal plates 50 14. Each plate has a hole fitted with a grommet 55 for sustaining the tube section 13, and an elongated slot 16, for a purpose to be noted. The arrangement at the right hand side is the same as the arrangement at the left hand side 55

but merely set upside down, so that no rights and lefts are required. The upper strip 9 on the one side is the same as the lower strip 10 on the other side, the strip 10 being reversed in direction.

I will accordingly describe the left hand arrangement since the right hand arrangement is the same thing reversed.

The lower end of the left hand strip 9 is formed with a slot 17, terminating in a round portion 18, into which the grommet of the tube supporting piece is thrust. It also has a slot 19, open to the back of the condenser arrangement. The upper end of the left hand lower piece 10 has a slot 20, facing upwardly and terminating in a rounded portion 21 for reception of the grommet on the supporting piece. It has also a closed slot 22, which is spaced from the portion 21, but which is an extension in the same direction of the slot 20.

There is a bolt 23 which passes through the supporting piece 14, and through the slots in the outside strips 9 and 10. When the two strips are in line this bolt passes through the elongated slot 16 in the piece 14, and slots 17 and 22 in the pieces 9 and 10. In this position shown in Fig. 3, the condenser is extended in a single plane, and held fast in this plane by the bolt.

By grasping the two sections of the condenser 30 and bending the lower half to a right angle with the upper half, which is permitted by the bending of the S shaped pipe, and the bending of the connector pipe 4, the bolt and supporting piece and outside strips can be brought to a 35 fixed right angle relation as shown in Fig. 5.

In this relation the bolt being first loosened, and the condenser bent to a right angle, the closed slot 22 of the lower outside strip 10, can be brought in line with the slot 19, in the upper strip 9. The bolt can then be moved along the slot in the supporting piece 14, until it passes through both the slots 22 and 19, and can then be fastened. In doing so the two strips 9 and 45 10 pivot on the grommet. When fastened the bolt holds the outside strips at a right angle.

When the condenser is so bent, it can be packed in such a way as to lie under the compressor unit, and thus require a packaging case very little larger than if the condenser were not packed. If the condenser had to be packed in a single extended relation, it would require a packing case as long as the condenser, and considerable in the way of supports for the remainder of the unit.

When received at the point for assembly, the operator will loosen the two bolts, slip them out of engaging position with the side pieces, bend the condenser back into straight relation, 60 and then slide the bolts to position to lock the side pieces in the extended relation.

The only difference as to the right hand side of the arrangement is that the tube supporting piece is reversed in position, and the bolt slides down instead of up in making the final straight line adjustment.

Other ways of arranging for a simple joint, lockable in two positions will suggest themselves, 70 and I do not limit my invention to the particular form shown. One essential item is that the condenser when shipped is in fully connected position with the rest of the refrigeration unit, which unit is charged with refrigerant. Therefore it is undesirable to have any unions or revo-

luble joints in the tubing, since all joints should be tightly sealed.

The precise construction of the two condenser sections is not a necessary item of my invention, the important feature being that there are two sections connected by a bendable tube section.

Having thus described my invention, what I claim as new and desire to secure by Letters Patent is:

1. A condenser for refrigeration units formed of a plurality of sections, each comprising tubular elements, a bendable tubular element between the sections, and side members for the sections, said side members having connections having locking means for holding the side members in extended and angular relation with each other, as desired.

2. In combination, a sectional condenser formed of tubular elements, having a bendable tubular element between sections, and side supports for said tubular elements for each section, said side support having connections between them pivoting about the said bendable tubular element, and securable in positions with the side supports in extended relation, and in positions 25 with the side supports at an angle with relation to each other.

3. In combination, a sectional condenser formed of tubular elements, having a bendable tubular element between sections, and side supports for said tubular elements for each section, 30 said side support having connections between them pivoting about the said bendable tubular element, and securable in positions with the side supports in extended relation, and in positions 35 with the side supports at an angle with relation to each other, the said connections comprising slotted plates through which the bendable tubular element passes, bolts for said slots, a slotted end on one of the side supports of each pair, an internal slot on the other side support of each pair, and a slot at an angle to the slotted end of the first noted supports, whereby the bolts passing through the slotted plates, may pass selectively either through the internal slot and slotted end, 45 or between the internal slot and the slot at an angle hereto.

4. A condenser for attachment to and shipment with a refrigeration unit assembly unit assembly in fully charged condition, comprising 50 a pair of like sections formed of tubular passages, a bendable tube connecting the sections, and framing for the sections having pivotal joints between the framing sections, said pivotal joints having locking means for holding them in a plurality of pivotal adjustments.

5. A condenser for attachment to and shipment with a refrigeration unit assembly in fully charged condition, comprising a pair of like sections forming tubular passages, a bendable tube 60 connecting the sections, and framing for the sections formed of side pieces, and links for joining them together in a plurality of locked positions.

6. A condenser for attachment to and shipment with a refrigeration unit assembly in fully charged condition, comprising a pair of like sections forming tubular passages, a bendable tube connecting the sections, and framing for the sections formed of side pieces, and links for joining them together in a plurality of locked positions, said framing and links being formed alike for the two sections but reversed in position at the two sides thereof.
